TELEPHONE SAVINGS BANK

William Langer and Leo Seidl, New York, N. Y.

Application May 23, 1950, Serial No. 10,108

Term of patent 7 years

(Cl. D34—11)

To all whom it may concern:

Be it known that we, William Langer and Leo Seidl, citizens of the United States and residents of, respectively, New York, in the county of Bronx and State of New York, and New York, in the county of Queens and State of New York, have invented a new, original, and ornamental Design for Telephone Savings Bank, of which the following is a specification, reference being had to the accompanying drawings forming part thereof, in which:

Figure 4 is a side elevation of the savings bank mounted on a telephone. The telephone is shown in dotted lines in combination with the savings bank for illustrative purposes only; and

We claim:

The ornamental design for a telephone savings bank, as shown and described.

WILLIAM LANGER.
LEO SEIDL.
